Patented Apr. 13, 1976

239,524

SERVICE STATION FOR AUTOMOBILES

Albert A. Perata, 48 Freeman Court, Walnut Creek, Calif.
94596, and Robert L. Sylvester, 200 Alice Lane, Orinda,
Calif. 94563

Filed Jan. 11, 1974, Ser. No. 432,432

Term of patent 14 years

Int. Cl. D25—03

U.S. Cl. D13—1 B

FIG. 1

FIG 2

FIG 3

FIG 4

FIG 5

FIG 6

FIG. 1 is a perspective view of a service station for automobiles showing our new design;

FIG. 2 is a top plan view thereof;

FIG. 3 is a front elevational view thereof;

FIG. 4 is a rear elevational view thereof;

FIG. 5 is an end elevational view thereof; and

FIG. 6 is another end elevational view thereof.

We claim:

The ornamental design for a service station for automobiles, substantially as shown.
